TRAILER

Jesse R. Birchard, Walled Lake, Clement Bondar, Beverly Hills, and Ray C. Conner, Battle Creek, Mich., and Albert D. Mortrude, Pompano Beach, Fla., assignors to Clark Equipment Company, a corporation of Delaware

Filed Sept. 20, 1968, Ser. No. 13,646

Term of patent 14 years

Int. Cl. D12—10

U.S. Cl. D14—3

FIG. 1

FIG. 2

FIG. 3

FIG. 4

FIG. 5

FIG. 6

The dominant features of our design reside in the portions shown in full lines.

We claim:

The ornamental design for a trailer, as shown and described.
